TION OF DELAWARE

METHOD AND MEANS FOR REMOVING CARBON DEPOSITS

No Drawing.

Application filed August 28, 1929. Serial No. 389,088.

This application relates to the removal of carbon deposits from the combustion chambers of internal combustion engines, and its principal objects are to employ compounds particularly suitable for this purpose and a process adapted to employ these compounds at their highest efficiency.

We have found that nitromethane is particularly useful in removing carbon deposits and that the best method of using it is to apply it to carbon coated parts which have been heated preferably to a temperature above 150° F., the optimum conditions for water cooled engines being at approximately the boiling point of water. We may also use with nitromethane a mixture of benzol and alcohol, or other low boiling varnish remover, which apparently increases the solvent action of nitromethane not only by reducing the viscosity, but also because they are lower boiling and tend to keep the liquid in contact with the carbon in a mild state of agitation.

As a specific example we may use in each cylinder of an ordinary six cylinder engine 30 c. c. of a mixture comprising by volume 40 parts of nitromethane, 30 parts of benzol, and 30 parts of ethyl alcohol. The engine is operated until the temperature of the metal parts of the combustion chamber is at least 150° F. when the mixture is injected or otherwise introduced into the cylinders and the engine stopped. The mixture is permitted to remain in the cylinders for about two hours more or less, depending upon the nature of the carbon deposit, during which time the gummy binder is softened or dissolved. Then the engine is started and the loosened deposit is gradually blown out the exhaust.

The proportion may be changed to suit specific conditions and the nitromethane may be used alone.

When cleaning the parts by hand they may be heated, the solvent applied, and when the binder is softened the deposit may be wiped off.

We claim:

1. The process of removing carbon deposits from the combustion chamber of an internal combustion engine which comprises applying to the carbon deposit nitromethane, and removing the carbon deposit.
2. The process of removing carbon deposits from the combustion chamber of an internal combustion engine which comprises heating the coated parts, applying to the carbon deposit nitromethane and a low boiling varnish remover, and removing the carbon deposit.
3. The process of removing carbon deposits from the combustion chamber of an internal combustion engine which comprises heating the coated parts to above 150° F., applying to the carbon deposit nitromethane, benzol and alcohol, and removing the carbon deposit.
4. A composition of matter for removing carbon deposits from internal combustion engines comprising nitromethane and a low boiling varnish remover.
5. A composition of matter for removing carbon deposits from internal combustion engines comprising nitromethane, benzol and alcohol.

In testimony whereof we affix our signatures.
